UNITED STATES PATENT OFFICE.

EVERETT W. McVICAR, OF MARLBORO, MASSACHUSETTS, ASSIGNOR TO UNITED SHOE MACHINERY CORPORATION, OF PATERSON, NEW JERSEY, A CORPORATION OF NEW JERSEY.

MANUFACTURE OF SOLES FOR SHOES.

Application filed August 8, 1919. Serial No. 316,136.

To all whom it may concern:

Be it known that I, EVERETT W. McVICAR, a citizen of the United States, residing at Marlboro, in the county of Middlesex and State of Massachusetts, have invented certain Improvements in the Manufacture of Soles for Shoes, of which the following description, in connection with the accompanying drawings, is a specification, like reference characters on the drawings indicating like parts in the several figures.

The present invention relates to improvements in the manufacture of shoes.

For purposes of illustration the invention is herein shown and described in its application to the manufacture of turn shoes and more especially turn shoes having rubber turn soles.

In the manufacture of turn shoes it is the usual practice to incorporate the shank stiffener in the shoe by cementing it to the upper surface of the sole because in this way the attachment of the stiffener to the sole does not appear on the tread or finished surface of the sole as would naturally occur if tacks or similar fastenings were driven through the stiffener and into the sole. This manner of attaching the stiffener to the sole is not entirely satisfactory because of the uncertainty and, in many instances, ineffectiveness of the cement as a fastening means which results in the stiffener failing to perform its intended functions in the shoe. When a rubber sole is employed in making a turn shoe, a cement attachment of the shank stiffener to the sole is entirely inadequate chiefly because a sole of this type can not be molded to the desired conformation during the manufacture of the shoe as can a leather sole, but must depend upon the stiffener to maintain its conformation, and consequently a considerable strain is placed upon the attaching means for the shank stiffener. Moreover, the surface of a rubber sole is not adaptable for cement.

It is an object of the present invention to produce an improved sole for shoes in which accurate and effective means are provided for attaching a shank stiffener to the sole and, also, to provide a convenient and efficient method of preparing a sole for the application of a stiffening member.

With the above and other objects in view,

the invention contemplates a novel rubber turn sole provided at the forward portion of its shank with a stiffener securing means comprising a pocket adapted to receive the forward portion of a shank stiffener, said pocket opening on to the upper surface of the sole forwardly of the heel breast line to enable the rearwardly projecting portion of a stiffener to lie upon the upper surface of the sole and on to the heel seat. As herein illustrated, this pocket is formed so as to confine the forward portion of the shank stiffener against lateral and forward movement relatively to the sole while the rear end of the stiffener is secured to the heel seat portion of the sole by a tack to prevent withdrawal of the shank stiffener from the pocket. The sole herein illustrated consists of a body portion of rubber compound and a reinforcing layer of canvas molded and vulcanized into an integral sole structure, and the stiffener receiving pocket is formed between the top canvas layer and the main body portion of the sole.

In accordance with the preferred practice of the invention, and as herein illustrated, the pocket in the sole is formed by providing the reinforcing blank with a transversely disposed slit in its shank portion, inserting a member having the approximate dimensions of the forward portion of a shank stiffener through the said slit and between the sole blank and the reinforcing layer, uniting the said two blanks and thereafter withdrawing the said device to produce a stiffener securing pocket in the forward shank portion of the sole. Conveniently the member used to form the pocket between the body portion of the sole and the reinforcing layer may be the shank stiffener itself, the stiffener being withdrawn from the sole after the pocket is formed and subsequently put in place again. By forming a stiffener securing pocket in the sole between its upper and lower surfaces as above described, the stiffener can be accurately and positively applied to the sole without the stiffener securing means being exposed on the exterior of the shoe or forming an objectionable protuberance on the interior of the shoe.

The invention will now be described in connection with the accompanying drawings

illustrating a preferred application of the invention and the novel features of the invention will then be defined in the appended claims.

5 Fig. 1 shows in perspective a preferred embodiment of the sole of the present invention;

10 Fig. 2 illustrates one step in the process of making the sole shown in Fig. 1, the several sole parts being shown in their assembled relation;

15 Fig. 3 shows the use of the sole in the manufacture of a turn shoe.

The sole of the present invention consists 20 of a body portion of rubber 2 and a reinforcing layer of canvas 4 the two layers being molded and vulcanized under pressure in a mold shaped and arranged to produce a marginally extending sewing rib 6 on the upper side of the sole, this sewing rib receiving 25 the stitches which attach the shoe upper to the sole.

In accordance with the present invention the sole is provided with a shank stiffener 30 securing means consisting of a pocket 8 shaped and arranged to receive the forward end portion of a shank stiffener 12, this pocket being of substantially the same dimensions as the dimensions of the forward 35 end portion of the stiffening member so that the stiffening member is confined against movement relatively to the sole.

This pocket is formed in the sole as herein illustrated by providing the shank portion 40 of the reinforcing layer with a transversely disposed slit 10, this slit being of substantially the same width as the stiffening member and being located preferably about midway between the ball line and the heel breast line of the sole. It will be noted 45 that with this location of the slit only the forward half of the stiffener device is received in the pocket while the rear half of the stiffener extends along the upper surface of the sole to the heel seat. In placing the rubber blank, together with the reinforcing layer 4, in the mold, a metal shank stiffener 12 or similar device is pushed through the slit in the reinforcing layer 4 so that its forward end extends between the rubber blank and the canvas layer, a sufficient length of the device being left projecting rearwardly to enable it to be withdrawn from the sole after vulcanization. The assembled sole is 55 then placed in a mold and the sole vulcanized under pressure in the customary manner. The portion of the stiffener lying between the rubber body and the reinforcing layer prevents the vulcanized union of these 60 two layers, and its subsequent withdrawal produces a pocket in the sole between the upper and tread surfaces of the sole. At the same time the rearwardly projecting portion of the stiffener is embedded in the upper surface of the sole thereby produc-

ing a recess orbed 14 to receive this portion of the stiffener with its upper surface flush with the upper surface of the sole.

To facilitate the subsequent withdrawal of the stiffener member from the sole it has 70 been found desirable to coat the forward portion of it with soapstone or like material.

After the vulcanized sole has been removed from the mold, the shank stiffener 75 is withdrawn by means of its rearwardly projecting portion so as to leave a pocket in the forward portion of the shank of the sole. The completed sole is thus provided with shank stiffener securing means which 80 will accurately position the stiffener on the sole and hold it against displacement both in the manufacture of the shoe and in the subsequent wear of the shoe.

In the use of the sole thus prepared the 85 shank stiffener is not finally applied to the sole until after the shoe has been lasted and sewed and preferably not until after the shoe has been turned right side out although under some conditions it may be found ad- 90 vantageous to apply the stiffener prior to turning the shoe right side out. By reason of the pocket 8 opening upon the upper surface of the sole substantially midway be- 95 tween the ball line and the heel breast line of the sole it has been found more desirable in practice, to turn the shoe right side out and then insert the forward end of the stiffener in the pocket. It will be seen that the pocket 8 serves to locate the end of the 100 stiffener 12 in proper central relation on the sole and, being of substantially the same dimensions as the stiffener, holds it securely in place. The rearwardly projecting portion of the stiffener seats itself in the recess 14 105 formed in the upper surface of the sole, and tacking the rear end of the shank stiffener to the sole within the heel seat area, prevents any shifting or movement of the stiffener. By forming the pocket to receive 110 the forward end of the stiffener in the sole in the manner described, the attachment of the stiffener does not damage or injure the finished tread surface of the sole and neither does it produce any objectionable irregular- 115 ity or other protuberance on the interior of the shoe to engage the foot. Of course the shank stiffener which is to be incorporated in the shoe will be longitudinally curved to correspond to the arch of the last or foot, 120 and the insertion of the forward half of the stiffener in the pocket and the attachment of the rear end of the stiffener to the sole acts to conform the shank portion of the sole to this longitudinal curvature. The strain of 125 the sole upon the stiffener is taken up by the reinforcing layer of canvas which, being intergrally united with the rubber, is effective in preventing the sole from returning to its normal flat condition.

Having thus described my invention, what I claim as new and desire to secure by Letters Patent of the United States is:

1. As an article of manufacture, a molded and vulcanized sole comprising a tread member of rubber compound and a covering member of fabric, the two members being vulcanized together throughout their extent except at a locality in the shank, there being formed between them at this locality an empty pocket shaped opening upon the surface of the sole to receive and confine the forward portion of a shank stiffener. 5
2. As an article of manufacture, a shoe sole comprising a rubber body portion and a reinforcing layer co-extensive with the said body portion, said body portion and said layer being vulcanized together in such manner as to provide a pocket between them adapted to receive and confine the forward portion of a shank stiffening element, said reinforcing layer having an opening approximately midway of the shank portion to provide access to the said pocket. 10
3. As an article of manufacture, a shoe sole having a pocket formed between its upper and tread surfaces shaped and located to receive and confine the forward end of a shank stiffener, and a recess in its upper surface communicating with the pocket shaped and located to receive the rear end of the stiffener. 15
4. As an article of manufacture, a molded and vulcanized shoe sole having a pocket leading into its interior from its upper surface shaped and arranged to receive the forward end portion of a stiffening element and provided with a shank stiffener the forward end of which is located in the said pocket and the rear end of which is fastened to the upper surface of the sole within the heel seat area to prevent withdrawing of the stiffener from the said pocket. 20
5. As an article of manufacture, a shoe sole comprising a rubber body portion and a reinforcing layer vulcanized thereto, there being formed between the layer and the body portion a pocket and communicating with the rear end of the pocket a recess in the upper surface of the sole, and a shank stiffener the forward portion of which is located in the pocket and the rear portion in the recess. 25
6. That improvement in the art of making shoe soles which consists in assembling a sole blank and a sole reinforcing blank having a transversely disposed slit in its shank portion, projecting through the said slit and between the said two blanks a means having the dimensions of the forward portion of a shank stiffening element, uniting the said two blanks and thereafter withdrawing the said means to produce a pocket in the sole to receive the forward portion 30 of a stiffening element. 35
7. That improvement in the art of making shoe soles which consists in assembling a sole blank and a sole reinforcing blank having a transversely disposed slit in its shank portion, projecting through the said slit and between the said two blanks a shank stiffener, leaving a portion of the said stiffener projecting rearwardly of the said slit, uniting the said two blanks throughout and then withdrawing the said stiffener by means of the rearwardly projecting portion from between the said two blanks to produce a pocket subsequently to receive the shank stiffener in the use of the sole. 40
8. That improvement in methods of making rubber soles which consists in assembling in a mold a rubber compound sole blank and a sole reinforcing blank having a transverse slit in its shank portion, projecting through the slit and between the said two blanks a metal device having the measurements of the forward portion of a shank stiffener, leaving a portion of the said element projecting rearwardly of the said slit, molding and vulcanizing the assembled sole; 45 and then withdrawing the said device to produce a pocket subsequently to receive the forward portion of a shank stiffener. 50
9. That improvement in methods of making rubber soles which consists in assembling in a mold a rubber compound sole blank and a sole reinforcing blank having a transverse slit midway of its shank portion, projecting through the slit and between the two blanks a means adapted to prevent vulcanization 55 of the said two blanks throughout an area corresponding to that of the forward portion of a shank stiffener, and then molding and vulcanizing the assembled sole. 60
10. That improvement in methods of making rubber soles which consists in assembling in a mold a rubber compound sole blank and a sole reinforcing blank having a transverse slit in its shank portion, providing a metal device having the measurements of the forward portion of the shank stiffener, treating the metal device to enable it to resist vulcanization to a rubber body, projecting the said device through the said slit and between the said two blanks leaving a portion of the 65 said device projecting rearwardly of the said slit, vulcanizing the sole, and then withdrawing the said device by means of the rearwardly projecting portion to produce a pocket subsequently to receive the forward portion of a shank stiffening element. 70
11. That improvement in methods of making rubber soles which consists in assembling in a mold a rubber compound sole blank and a canvas reinforcing blank having a transverse slit in its shank portion, projecting through the slit and between the said two blanks the forward end portion of a shank stiffener, leaving a portion of the said ele- 75

ment projecting rearwardly of the said slit upon the heel seat portion of the sole, vulcanizing the sole under pressure and then withdrawing the said stiffener by means of 5 the rearwardly projecting portion to produce a pocket subsequently to receive the forward portion of the shank stiffener.

12. That improvement in methods of making rubber soles which consists in assembling 10 in a mold a rubber compound sole blank and a canvas reinforcing blank having a transverse slit midway of its shank portion, projecting through the slit and between the said blanks a means adapted to form a 15 pocket between the said two blanks to receive the forward portion of a shank stiffener and then vulcanizing the sole under pressure and withdrawing the said device by means of the rearwardly projecting portion 20 to produce a pocket subsequently to receive the forward portion of the shank stiffener.

13. That improvement in methods of making rubber soles which consists in assembling 25 in a mold a rubber compound sole blank and a blank of canvas material having a transverse slit located centrally of its shank portion, applying a shank stiffening member in position on the canvas layer with its forward

end projecting through the slit and between 30 the said two layers, vulcanizing the assembled sole under pressure and then withdrawing the shank stiffener to produce a pocket subsequently to receive the forward end portion. 35

14. As an article of manufacture, a molded and vulcanized sole having a pocket formed between its tread and upper surfaces to receive the forward portion of a shank stiffener, said pocket opening upon 40 the upper surface of the shank portion of the sole, and a shank stiffener having its forward end portion located in said pocket and extending rearwardly of said pocket upon the surface of the sole. 45

15. As an article of manufacture, a shoe sole comprising a rubber body portion and a reinforcing layer, said body portion and layer being vulcanized together in such manner as to provide a pocket having its open end leading out to the upper surface of the sole so as to be adapted to have inserted therein the forward end of a shank stiffening element. 50

In testimony whereof I have signed my 55 name to this specification.

EVERETT W. McVICAR.
